POROUS BOOT OR SHOE SOLE

Hermann Schulze, Leipzig, Germany

Application March 19, 1934, Serial No. 716,281
In Germany June 23, 1933

2 Claims. (Cl. 36-

This invention relates to a boot or shoe sole, of rubber or similar material, provided with tread studs or projections and with holes or perforations.

According to the present invention, the perforations or holes are located at the weakest places of the sole material and therefore between the projections or tread studs. Moreover the holes or perforations disposed between the studs are preferably provided in the middle portion of the sole, whilst, in the vicinity of the edges, the sole is left in an unperforated condition.

Attempts have already been made to provide holes in smooth rubber soles, that is, soles unprovided with projections or tread studs. These known embodiments, however, are attended with the defect that the upper edges of the holes, at the point of intersection with the surface of the tread, come into direct contact with the dirt or the like so that the holes become clogged, and the "breathing" of the soles, attained by means of the perforations, is rendered illusory. Moreover, in the case of smooth soles, the durability is also lessened as the result of perforation.

The boot or shoe sole of the present invention fundamentally avoids the defects of the soles hitherto known. The location of the perforations or holes between the tread studs, and therefore in the weakest portions of the sole produces an improved effect which should not be underestimated, namely, that the smallest and weakest surface is available for the attachment and adhesion of the dirt that lodges in the holes. Since, in walking, the sole naturally acts on the weakest points, through the pressure on the projections, the holes, which may have become occupied by dirt, are compressed and re-expanded, thus automatically dislodging said dirt. The space between the raised studs and the weaker places, which are situated at a much deeper level and in which the holes are located, enables any dirt that adheres to the soles to drop out with ease.

It is also important that the soles should be so perforated that said perforations are preferably located in the middle portion of the sole, so that the latter is left solid in the vicinity of the edges.

In order more clearly to understand the invention, reference is made to the accompanying drawing which illustrates diagrammatically and by way of example, a typical embodiment of shoe-

sole according to the invention, and in which:—

Fig. 1 is a plan of the sole; and

Fig. 2 a section of same.

In said drawing, *a* denotes the leather outer sole, to which the sole *b* of the present invention is secured, by cementing, in the known manner. As can be seen from the section, the sole itself is provided with projections or tread studs, between which—and therefore at the weakest parts of the sole material—are located the "breathing" holes *c*.

As can be seen from Fig. 1, in order to provide an unperforated edge, the holes or perforations do not extend right up to the edge of the sole. In addition to the advantages hereinbefore described, the cementing of the sole is facilitated, inasmuch as, in attaching the sole according to the invention, any air that is present between the leather-sole and the applied sole can quickly escape at all points, and the formation of bubbles further in is also prevented. Since, in the embodiment according to the invention, the flexibility of the sole is increased, it adapts itself to all the irregularities of the ground, and the protrusion of the sole beyond the edge of the shoe is thereby substantially diminished.

Having now particularly described and ascertained the nature of my said invention and in what manner the same is to be performed, I declare that what I claim is:—

1. A boot or shoe sole of rubber or the like material having a plurality of relatively thick portions defining a plurality of spaced studs, said studs being connected by relatively thin portions of said sole having apertures formed therein and providing a plurality of flexing elements between said studs to change the shape of the apertures when said sole is flexed.

2. A boot or shoe sole of rubber or like material having a plurality of relatively thick portions defining spaced rows of studs, said studs being connected by relatively thin portions of said sole, said thin portions being provided with apertures in an area less than that of the whole sole so that rows of studs and an imperforate portion of the sole bound the edge portions of the sole, the thin portions of the sole providing a plurality of flexing elements between said studs to change the shape of the apertures when the sole is flexed in use.

HERMANN SCHULZE.
